UNITED STATES PATENT OFFICE.

JOHN A. SWANSON, OF BANTRY, NORTH DAKOTA.

DRILL ATTACHMENT.

1,171,556.

Specification of Letters Patent. Patented Feb. 15, 1916.

Application filed August 21, 1915. Serial No. 46,751.

To all whom it may concern:

Be it known that I, JOHN A. SWANSON, a subject of the King of Sweden, residing at Bantry, in the county of McHenry and 5 State of North Dakota, have invented certain new and useful Improvements in Drill Attachments, of which the following is a specification, reference being had to the accompanying drawings.

10 This invention relates to new and useful improvements in guides and cleaners and more particularly to a device adapted to be applied to a disk drill or cultivator, the main object of the present invention being 15 the provision of a device which is adapted to be applied to the supporting standards of the disk and arranged upon the outer sides of the disks to guide the same and, at the same time, clean the dirt and other material 20 which might adhere thereto.

It is the purpose of my invention to provide such a device as can be readily applied to drills known as Monitor drills or any other drill of a like character. These drills 25 are so constructed that after a short period of use, the hubs of the forwardly convergent disks become so worn that the two disks, which should nearly touch each other, become separated to such an extent that the 30 hubs have to be ground down again in order to make the disks of any use.

As stated before, it is the object of my 35 invention to provide a guide acting to retain the convergent portions of the disks in proximity to each other even though the hubs of the disks become worn, this guide being so formed as to scrape or clean the disks of dirt.

Another object of the invention is to provide 40 a very simple device of this character which may be very cheaply made and readily applied to practically all makes of disk drills.

Another object of the present invention 45 is the provision of a guide and cleaner of the above character which will possess advantages in points of efficiency and durability, is inexpensive to manufacture and, at the same time, is simple in construction 50 and operation.

With the above and other objects in view, the invention consists in the novel features of construction, combination and arrangement of parts as will be hereinafter referred 55 to and more particularly pointed out in the specification and claims.

In the accompanying drawing forming a part of this application, Figure 1 is a side elevation illustrating my improved guide cleaner as applied to a rotary disk drill. 60 Fig. 2 is a top plan view of the device; and Fig. 3 is a front end elevation.

Referring more particularly to the drawing, 1 indicates the usual supporting frame of a disk drill and 2 the disk supporting 65 member upon the lower end of which are mounted the rotatable forwardly converging disks 3. Extending outwardly from the frame 1, is a flange 4 and arranged in parallel relation therewith, is a supporting bar 5. 70 The body of the cleaner or guide includes a flat plate 7 adapted to be arranged upon one side of the bar 5 and rigidly secured to the bar 5 and the flange 4, by means of the bolts 6. One end of the plate 7 is provided with 75 spaced elongated openings 9, whereby to receive the securing bolts 6 which thus adjustably secure the plate to the flange 4 and the bar 5. The outer end of the plate 7 is longitudinally slotted, as shown at 11 to 80 form the spaced blades 12, said blades being disposed substantially obliquely with respect to the body of the bar and the cutting edges 13 thereof being arranged in a forwardly convergent relation so as to engage 85 upon the outer faces of converging disks *a* as shown in dotted lines in Fig. 2. The convergent relation of the cutting edges 13 causes them to bear against the outer faces 90 of the disks and retain the same in their operative positions and, at the same time, scrape the dirt and other substance therefrom. It will be seen that the blades 12 are disposed at a downward and rearward inclination relative to the body of the plate 7 95 and that these blades are also outwardly and laterally inclined. Thus the mud which is scraped from the wheels will be guided outward and rearward and at the same time the material from which the blade is made is 100 such as to cause the blades to strongly resist any bending strain.

The slot which bifurcates the plate 7 to form the blades 12 with the cutting edges 13 is enlarged at its inner end to form a 105 circular opening 13^a having a diameter greater than the space between the cutting edges 13. The object of this is two-fold. If this slot were straight, that is, if the side edges 13 were continuously convergent 110 to the inner extremity of the slot, the disk in wearing would soon cut into the attach-

ment, whereas by having the slot terminate in an enlarged opening the cutting edge of the disk moves freely and wear is only on the side and as a consequence the attachment 5 will wear a great deal longer than it otherwise would. In the second place, if these disks are made of steel or material which can be bent to a degree after they have been in use for some time and are worn, 10 the blades can be sprung together a little, thereby taking up the wear and drawing the disks toward each other as with a new attachment. If the slot bifurcating the plate did not terminate in an enlarged opening, 15 it is apparent that this could not be accomplished, at least with any degree of satisfaction.

It will be noted that the plate 7 is secured to the supporting member 4 in such a manner 20 that it may be readily adjusted according to the various sizes of disks which may be used in connection with the drill. The adjusting bolts 6 may be quickly and readily removed from the openings 9 and replaced 25 in a very short space of time, so that the guide and scraper may be quickly and readily adjusted. It will be apparent that the guide and cleaner may be attached to drills, cultivators or any other form of implement 30 wherein forwardly converging rotary disks are used. The device itself, is extremely simple in construction and can be manufactured and applied to any other well known make of drill at a comparatively low 35 cost.

While I have shown and described the preferred form of my invention, it will be obvious that various changes in the details 40 of construction and in the proportions may be resorted to for successfully carrying my invention into practice, without sacrificing any of the novel features or departing from the scope of the invention, as defined by the appended claims.

Having thus described this invention, 45 what I claim is:—

1. A device of the class described including an elongated plate having spaced openings formed therein, one end of said plate 50 being longitudinally slotted to form spaced blades, said blades being arranged obliquely with respect to each other and converging inwardly toward their inner edges, said blades being disposed diagonally with respect to the plate, and means whereby to

support said plate, as and for the purpose set forth.

2. The combination with the forwardly converging disks of a drill and a frame supporting said disks including a member 60 disposed substantially in line with the axis of the disks, of a device mounted upon said member for holding the disks in convergent relation including a body adjustably mounted upon the member for movement toward 65 and from the axis of the disk and having rearwardly divergent extensions engaging on the outer faces of the disks and holding them in proximity to each other, said extensions being downwardly and laterally deflected and acting as scrapers.

3. The combination with the frame and convergently related disks of a disk drill, of means for holding the said disks in convergent relation including a substantially 75 flat plate adjustably mounted upon the frame for movement toward and from the axis of the disk, the plate at its rear end having an approximately V-shaped slot formed in it to provide extensions of the 80 plate having rearwardly diverging inner edges engaging on the outer faces of the disks and holding them in proximity to each other.

4. A guide and cleaner of the character 85 described including a supported member formed at one end to provide outwardly and convergently related spaced walls adapted to engage on the outer faces of a pair of converging disks and retain said disks in 90 proximity to each other, the convergently related spaced walls terminating at their inner ends in a relatively enlarged opening.

5. A guide and cleaner of the character 95 described including a plate bifurcated at one end to provide blades having their inner edges convergently related and adapted to engage on the outer faces of a pair of converging disks and retain said disks in proximity to each other, the bifurcation defining 100 said blades terminating at its inner end in an enlarged opening greater in width than the space between the cutting edges of the blades.

In testimony whereof I hereunto affix my 105 signature in the presence of two witnesses.

JOHN A. SWANSON.
